UNITED STATES PATENT OFFICE.

BEN F. HARDESTY, OF ST. LOUIS, MISSOURI.

SPRING-EQUALIZER ATTACHMENT FOR AUTOMOBILES.

1,388,461.

Specification of Letters Patent. Patented Aug. 23, 1921.

Application filed January 24, 1920. Serial No. 353,905.

To all whom it may concern:

Be it known that I, BEN F. HARDESTY, a citizen of the United States, residing at St. Louis, Missouri, have invented a certain 5 new and useful Improvement in Spring-Equalizer Attachments for Automobiles, of which the following is a full, clear, and exact description, such as will enable others skilled in the art to which it appertains to make and 10 use the same, reference being had to the accompanying drawings, forming part of this specification, in which—

Figure 1 is a front plan view of my improved spring equalizer attachment for automobile.

Fig. 2 is an edge elevational view taken on the line 2—2 of Fig. 1.

Fig. 3 is a detail view.

Fig. 4 is a plan view of a blank.

20 Fig. 5 is a top plan view of a modified form.

Fig. 6 is a plan view of the blank shown in Fig. 5.

Fig. 7 is a top plan view of another modified form.

Fig. 8 is a plan view of the blank from which the attachment shown in Fig. 7 is formed; and,

Fig. 9 is a top plan view of another modified form.

This invention relates to a new and useful improvement in a spring equalizer attachment for automobiles and consists in the formation of the bell-crank lever from 35 pressed or wrought metal forming a part of a spring equalized disclosed in an application filed by me of even date herewith.

The spring equalizer partially shown in Fig. 1 consists of the usual leaf spring 1 of 40 a well known type of automobile (Ford) which is supported by a shackle 2 pivotally mounted in the upper end of a bell-crank lever 4 fulcrumed on a reversed spring perch 3 mounted in the axle 5 of the machine. 6 45 is a rod upon which is mounted the shock-absorbing means, said rod being duplicated on the opposite side of the machine so that when either front wheel is suddenly lifted, the shock or jar will not be transmitted to 50 the leaf springs 1. The constructions of the springs for absorbing these shocks or jars are not shown in this application, as they form the subject matter of the co-pending application above referred to.

This invention relates particularly to the 55 construction of the bell-crank lever which is preferably made of one piece of stamped metal bent at each end upon itself to form a fulcrum and pivotal support for the shackle (at its upper end), the lower end 60 being bent upon itself to form a slot having a semicircular recess at its outer edge to receive a semicircular washer 7 arranged on the rod 6 so that said rod may have a rocking movement relative to said fulcrum 65

In Figs. 1 to 4, 4 indicates the body portion of the bell-crank whose upper end is folded upon itself so that it is provided with a jaw 4^a perforated at 4^b to receive the pivot bolt 8 arranged in the upper end of the 70 spring perch, said jaw 4^a being connected to the main body portion of the blank by an inner end connection 4^c. The lower end of the bell-crank lever is folded or bent upon itself, as at 4^d, to form a slotted opening and 75 the edges are recessed at 4^e to form a seat for the semicircular washer 7,—the folded lower end providing a slot through which the rod 6 passes.

In Figs. 5 and 6, I have shown a bell-crank 80 lever and blank therefor, respectively, in which the upper end of the blank is formed with a projection or leg 9 designed to fit in and be riveted or upset in an opening 9^a, the lower end of the blank being folded upon 85 itself as described with reference to Figs. 1 to 4.

In Figs. 7 and 8, the blank is formed so that there is a bridge wall 10 extending over the top of the shackle and connecting the 90 two side walls of the bell-crank lever, the lower end being folded upon itself to form the slotted edge recessed opening before described.

In Fig. 9, the blank is formed so that there 95 is a bottom bridge wall 11 connecting the two vertical walls of the upper end of the bell crank lever, the lower end of said bell-crank lever being folded upon itself to form a recessed slotted seat for the semispherical 100 head of the rod 6 as before described.

I claim:

1. A spring equalizer attachment for automobiles in the form of a bell crank lever consisting of an arm folded upon itself and 105 recessed at its edges to form a slotted opening through which an equalizer rod may pass, the other arm of said bell crank lever

having its outer end formed to provide separated jaws for the attachment of the spring shackle.

2. A spring equalizer attachment for automobiles comprising a blank bent upon itself and provided with perforations to form a fulcrum, and means of attachment for the

spring shackle, the opposite end of said blank being recessed at its edges and bent upon itself to form a slotted opening 10 through which an equalizer rod may pass.

In testimony whereof I hereunto affix my signature this 20th day of January, 1920.

BEN F. HARDESTY.
